CIRCUIT BREAKER

Leonard J. Linde, Aldan, Pa., assignor to General Electric Company, a corporation of New York

Application February 5, 1935, Serial No. 5,036

10 Claims. (Cl. 200—116)

My invention relates to circuit breakers, more particularly to circuit breakers of the trip-free type in which the circuit controlling contacts are manually operable between open and closed circuit positions and are automatically operable to open circuit position upon the occurrence of predetermined abnormal current conditions, and has for an object the provision of a circuit breaker of this type which is simple and reliable in its operation and inexpensive to construct.

Circuit breakers of this general type when provided with suitable arc extinguishing devices so as to combine the protective features of a fuse and the advantages of a manually operable switch, have found considerable application in the control of distribution and feeder circuits. When applied to the control of circuits of this type, the circuit breaker for convenience of operation is sometimes mounted upon a panel board, and the permissible physical dimensions of the circuit breaker and its enclosing casing are necessarily rather limited. At the same time, severe operating conditions are often encountered, especially in industrial applications.

It has heretofore been proposed to employ multipole circuit breakers in installations of this type in which a single operating mechanism is provided for opening and closing all of the circuits, the operating mechanism at the same time being automatically responsive to current conditions in the individual circuits. However, much is yet to be desired in a circuit breaker of this type which is compact and rugged and which will quickly interrupt currents of considerable magnitude without loud explosions or destructive arcing. Accordingly, it is a further object of my invention to provide a circuit breaker of this type for interrupting large currents which is of compact and rugged construction and is reliable in its operation.

In carrying out my invention in one form, I provide a circuit breaker comprising a pair of relatively movable contacts, manually operable means for actuating one of said contacts between open and closed circuit positions and means comprising a normally latched tripping lever biased by suitable tripping springs for quickly actuating one contact to open circuit position upon the occurrence of abnormal current conditions, the manually operable mechanism and the automatic tripping mechanism being so overlapped and nested together as to occupy a minimum of space and to produce a compact and sturdy arrangement. More specifically, I provide a multipole circuit breaker provided with a plurality of pairs

of relatively movable contacts, each pair of contacts being enclosed in an explosion-proof, arc extinguishing chamber, a single manually operable mechanism for opening and closing the contacts with a snap action, normally latched tripping means for operating the contacts to open circuit position and current responsive means for releasing the tripping means upon the occurrence of predetermined abnormal current conditions in any one of the pole circuits.

For a more complete understanding of my invention, reference should now be had to the drawings in which Fig. 1 is a plan view of a circuit breaker embodying my invention, the cover of the circuit breaker and certain parts thereof being removed to show the operating mechanism; Fig. 2 is a sectional view taken along line 2—2 of Fig. 1; Figs. 3 and 4 are fragmentary sectional views showing the operating mechanism of the circuit breaker in different positions; Fig. 5 is an end view, partly in section, of the circuit breaker operating mechanism; and Fig. 6 is a detailed view in exploded perspective of the operating mechanism of the circuit breaker.

Referring to the drawings, I have shown my invention in one form as applied to a multipole circuit breaker comprising a base 10 formed of molded insulation for supporting a plurality of terminal members 11 and 12, a plurality of circuit interrupting or arc extinguishing devices 13, an improved operating mechanism embodying my invention indicated generally by the reference numeral 14 and a current responsive trip device indicated generally by the reference numeral 15. Suitable insulating barriers are provided for preventing flashover or short circuit between the individual poles of the circuit breaker, the barriers 16 and 17 being integral with the base 10 and extending respectively from the opposite ends thereof to the operating mechanism 14 and to the trip device 15 which are respectively provided with the insulating barriers 18 and 19 arranged substantially in alignment with the barriers 16 and 17. The circuit for each pole of the circuit breaker is substantially the same and extends from one of the terminal members 11 through the interrupter device 13 across the operating mechanism by way of a flexible conductor 20 and through the trip device 15 to one of the terminal members 12.

Each of the circuit interrupting devices 13, which are of the type described and broadly claimed in a copending application of Ludwig S. Walle Serial No. 667,856, filed April 25, 1933, entitled "Circuit breakers" and assigned to the same

assignee as the present invention, comprises a compression chamber which includes a cylindrical casing 21 of suitable pressure resisting material, enclosing a fixed contact 22 and a reciprocally movable contact 23. A cylindrical liner 24 of kerosene-free fiber is arranged within the cylinder 21 surrounding the contacts and in order to gas tightly to seal the fixed contact end of the cylinder 21 and to provide a rigid support for the fixed contact, a sealing cup 25 of suitable material such as soft copper, a pair of insulating bushings 26 and 27 and an insulating washer 28 are provided. It will be apparent that when the nut 29 is tightened down on the threaded end 30 of the fixed contact, the insulating members 26, 27 and 28 will be wedged tightly together by an enlarged shoulder 31 formed on the fixed contact 22 and by a wedge-shaped flange 32 on the cylinder 21 to form a gas tight closure for this end of the compression chamber and a rigid support for the fixed contact 22.

The movable contact end of the compression chamber is provided with a cylindrical cap 33 which threadedly engages the cylinder 21 and is provided with a sealing gasket 34. Supported by the cap 33 is a plug 35 in which the movable contact 23 is slidably journaled. In order to provide for snap action of the movable contact 23 while at the same time substantially sealing 30 the compression chamber, a pair of sealing washers 36 of leather or other suitable material are provided, and the movable contact 23 is provided with a shoulder 37 arranged to engage a conical valve seat 38 formed in the cap 33 gas tightly to seal this end of the compression chamber when the movable contact is in open circuit position. The particular features of the compression chamber and the sealing means therefor form no part of the present invention and are fully described and claimed in another application of 40 Ludwig S. Walle, Serial No. 4,448, filed Feb. 1, 1935, entitled "Circuit breakers" which application is assigned to the same assignee as the present invention.

In order simultaneously to operate all of the movable contacts 23 between open and closed positions, I provide an insulated crossbar 39 which extends across all of the poles of the circuit breaker and is journaled at its ends in the bearings 40 carried by the base 10. Each of the movable contacts 23 is connected to the crossbar 39 by a resilient lost-motion connection which includes a pin 41 supported by the legs of a U-shaped member 42, the yoke portion of 50 which comprises a frame 42a which surrounds the crossbar 39. Each of the pins 41 extends through a slot 43 in a block 44 fixedly secured to the associated movable contact 23. As shown in Fig. 2, each of the movable contacts 23 is 55 drilled to accommodate a spring 45 one end of which bears against the contact 23 and the other end of which is engaged by the pin 41.

In a copending application of Charles H. Hill, Serial No. 18,127, filed April 25, 1935, entitled 60 "Circuit breakers," which application is assigned to the same assignee as the present invention, there is described and claimed a circuit breaker having an operating mechanism comprising a contact operating toggle, one link of which comprises a three-point crank lever, overcenter 65 spring means for rotating the crank to make and break the toggle, and a tripping arm biased for movement to break the toggle independently of the overcenter spring means. The invention disclosed in the above application was made by

the said Charles H. Hill prior to my invention and I, therefore, do not herein claim anything shown or described in that application, which is to be regarded as prior art with respect to the present invention.

My improved operating mechanism for actuating the crossbar 39 to move all of the contacts 23 between open and closed circuit position is arranged adjacent the movable contact end of the interrupting devices 13 on a frame which 10 comprises a pair of spaced supporting walls 46 carried by a supporting block 47 which is fastened to one of the cylinders 21 by the screws 48. As may be seen best by reference to Fig. 6, each of the supporting walls 46 includes an 15 elongate portion extending along the cylinder 21 and provided with slots 49 and 50 and a laterally extending portion which overhangs the movable contact ends of the cylinder. The slots 49 are elongate as shown and serve as guides in a manner to be fully described later.

Carried by the overhanging portion of the supporting walls 46 is a pivot pin 51, the outwardly extending ends of which pivotally support a U-shaped operating member 52 which is 25 provided with an insulating handle 53 arranged to extend through a suitable aperture 54 in the circuit breaker cover 55, as shown best in Fig. 2. A second pivot pin 56 extends between the portions of the supporting walls 46 which nest with 30 in the legs of the U-shaped operating member 52 and pivotally supports a pair of parallel switch operating arms 57, the other ends of which carry an operating pin 58. Extending between the arms 57, I provide a pair of bracing 35 members 57a. These braces are not shown in Fig. 6 in order to simplify the drawings. Pivotally supported on a third pivot pin 59 carried by the frame walls 46, I provide a pair of three-point or substantially triangular toggle links 60 each 40 of which is provided with a slot 61 through which the respective ends of the operating pin 58 extend. Connected to each of the three-point toggle links 60 is one of a second pair of toggle links 62, the adjacent opposite ends of which 45 links pivotally engage a pin 63 carried by the legs of a U-shaped member 64 the yoke portion of which surrounds and is secured to the crossbar 39.

In order to make and break the toggles which comprise the links 60 and 62, to move the crossbar 39 and the movable contacts connected thereto between open and closed circuit positions with a snap action, I provide a pair of overcenter spring devices connected between the operating pin 58 and the U-shaped operating member 52. Each of the overcenter spring devices, as shown best in Fig. 6, comprises a U-shaped frame 63a pivotally connected to the operating pin 58 adjacent the open end of the U, and a yoke member 64a pivotally carried by one of the pins 65 which extend outwardly from the U-shaped operating member 52. Extending from the yoke member 64a is a pair of plunger rods 66 which slidably extend through the end of the U-shaped frame 63a, each of the plungers being surrounded by a compression spring 67 the adjacent ends of which bear against the end of the U-shaped frame and the other ends of which bear against a plate 68 carried by the plungers, 60 portions of the plate 68 being cut away as indicated by the reference numeral 69 to slidably engage the legs of the U-shaped frame 63a which serve as guides therefor. It will be apparent that the compression springs 67 are arranged nor- 70 75

mainly to hold the yoke member 64a in engagement with the end of the U-shaped frame 63a, and to resist relative movement therebetween, the arrangement being such that the device acts 5 as a strong tension spring connected between the operating member 52 and the operating pin 58.

In Fig. 2 I have shown the circuit breaker in its closed circuit position, and it will be apparent that when the insulated handle 53 is moved downwardly to the position shown in Fig. 3, the U-shaped operating member 52 will be moved about its pivot 51 so as to carry the adjacent ends of the overcenter spring devices downwardly until the line of action thereof is carried overcenter relative to the pivot pin 56. As soon as the overcenter spring devices pass overcenter relative to the pivot pin 56, the operating pin 58 which is carried by the switch operating arms 57 will be moved downwardly with a snap action, thereby moving the three-point toggle links 60 about the pivot pin 59 to break the toggles and operate the crossbar 39 and the movable contacts connected thereto to the open circuit position shown in Fig. 3. Similarly, movement of the operating handle 53 from the position shown in Fig. 2 to the uppermost position shown in Fig. 3 will be effective to move the operating pin 58 to make the toggles and return the crossbar 39 and the movable contacts 23 to the closed circuit position.

It will of course be apparent that the toggle making and breaking force exerted by the overcenter spring devices will depend not only upon the strength of the springs 61 but upon the displacement of the line of action thereof from the pivot pin 56. By disposing the operating member 52 and the switch arms 57 in partially overlapping relation on the spaced pivot pins 51 and 56, not only is a more compact structure effected but also a relatively large displacement of the overcenter spring device relative to the pivot pin 56 is obtained with a small angular movement of the operating member 52.

The circuit breaker is also adapted for automatic operation to open the circuit upon the occurrence of predetermined abnormal current conditions and accordingly, I provide a pivoted tripping member 70 and a pair of tripping springs 71 (Figs. 1 and 2), the operation of which is controlled by the trip device 15. This trip device, which will be more fully described later, includes a latch finger 72 arranged normally to engage the yoke portion 73 of the tripping member 70 which is substantially U-shaped, as shown best in Fig. 6, and is pivoted adjacent the open end of the U on the extending ends of the pin 51, each leg of the U being provided with the portions 74 and 75 which respectively extend laterally on opposite sides of the pivot. As shown best in Figs. 1 and 2, the tripping springs 71 are disposed between the elongate portions of the frame walls 46 with the ends thereof which are adjacent the tripping member 70 engaging a fixed crossbar 76 supported in the slots 50 and the ends which are remote from the tripping member 70 engaging a movable crossbar 77 slidably supported in the slots or guides 49 with its ends extending therethrough and respectively connected to a pair of operating straps 78. Each of the straps 78 extends along one of the walls 46 and is provided with a hook-shaped end 79 which engages one of a pair of pins 80 extending from the portion 74 of the tripping member 70.

It will be observed that each of the crossbars 76 and 77 is provided with a pair of fingers 81 which extend a short distance into the respective

ends of the tripping springs 71 to guide the same, and that each of the springs 71 is surrounded by a supporting cylinder 82 which cooperates with the fingers 81 to maintain the tripping springs 71 in proper alignment between the crossbars 76 and 77. 5

Any suitable trip device may be provided for releasably latching the tripping member 70 in its normal position against the bias exerted by the tripping springs 71 and for releasing the tripping member upon the occurrence of abnormal current conditions. The force exerted by the tripping springs 71, however, is of considerable magnitude and accordingly, I prefer to use a rugged trip device of the type described and claimed in a copending application of John L. Lappin, Serial No. 4,659, filed Feb. 2, 1935, entitled "Circuit breakers", which application is assigned to the same assignee as the present invention.

This trip device 15 may be described for the purposes of the present application as comprising a subbase 83 suitably fastened to the circuit breaker base 10, the before-mentioned insulating barriers 19 being formed integral therewith. Supported centrally of the subbase 83 is a frame comprising the spaced walls 84 between which are supported a latch plate 85 pivoted at 85a, a U-shaped impact member 86 pivoted at 86a and a U-shaped reset member 87 pivoted at 87a. The latch plate 85 carries the previously referred to latch finger 72, and the yoke portion of the U-shaped impact member 86 is overturned to provide a striking surface 88 for engaging a portion of the latch plate 85 nested therein. Each leg of the impact member 86 carries a pin 89 extending through a slot 90 in one of the supporting walls 84 and arranged to engage a cam finger 91 provided on the U-shaped reset member 87, the yoke portion of which is interposed in the path of the tripping member 70.

Suitable springs 92 are provided for operating the impact member 86 about its pivot 86a in a counterclockwise direction to strike the latch plate 85 a hammerlike blow and thereby move the latch finger 72 to release the tripping member 70, and a pair of resetting springs 93 are arranged to operate the reset member 87 about its pivot 87a in a counterclockwise direction to return the impact member 86 to the position shown in the drawings after each operation thereof to striking position. The impact member 86 is normally held in the position shown in the drawings by a trip bar 94 which extends across the three poles of the circuit breaker and is pivoted adjacent its ends on a pin 94a, the trip bar being normally biased by a spring 95 to engage a finger 96 carried by the impact member.

Associated with each pole of the circuit breaker is a thermal and a magnetic device for moving the trip bar 94 about its pivot to release the impact member 86. Each thermal device comprises a bimetallic element 97 arranged to be heated in accordance with the current in the associated pole of the circuit breaker and adapted to engage an insulating button 98 carried by the trip bar 94 to move the trip bar about its pivot upon the occurrence of an overload of sufficient magnitude and duration to flex the bimetallic element. Each of the magnetic devices comprises a U-shaped magnetic member 99 arranged to have a flux induced therein by the current in the associated pole of the circuit breaker to attract an armature 100 which is pivoted on the pin 94a and extends across the three poles of the circuit breaker, the armature being provided with a finger 101 for engaging an adjustable pin 102 on the 75

trip bar 94 to move the trip bar about its pivot upon the occurrence of a sufficiently high overload to cause the armature to be attracted by one or more of the magnets 99.

- 5 In Fig. 2 of the drawings, the circuit breaker is shown in its closed circuit position with the tripping member 70 held in its latched position by the latch finger 72 of the trip device 15 against the force exerted by the tripping springs 71. It 10 will be observed that in this position of the circuit breaker the extending portions 75 on the tripping member 70 are disposed adjacent the operating pin 58 but out of engagement therewith.

- 15 Upon the occurrence of abnormal current conditions in the circuit breaker the trip bar 94 will be moved about its pivot by one or more of the thermal or the magnetic current responsive devices, depending upon the nature of the abnormal 20 current conditions, to release the impact member 86 for operation in a counterclockwise direction about its pivot 86a by the springs 92 whereby the striking portion 88 of the impact member will strike the latch plate 85 a hammerlike blow and move the latch finger 72 out of engagement with the yoke portion 73 of the tripping member 70. As soon as the latch finger 72 is disengaged from the yoke 73, the tripping member 70 will be operated in a clockwise direction about its pivot point 51 by the tripping springs 71 and the extending portions 75 will engage the operating pin 58, the force exerted by the tripping springs 71 being of sufficient magnitude to move the operating pin 58 against the force exerted by the 30 overcenter spring devices to the position shown in Fig. 4, thereby breaking the toggle and operating the crossbar 39 and the movable contacts 23 to open circuit position. It will be observed that the tripping member 70 carries a suitable target 35 103 which is arranged to cooperate with an aperture 104 in the insulated handle 53 to give a visual indication that the circuit breaker has been automatically tripped to open circuit position.

- 40 To reclose the circuit breaker after it has been automatically tripped to open circuit position, it 45 is necessary first to move the handle 53 from the position shown in Fig. 4 downwardly to the position shown in Fig. 3. This movement of the handle 53 is effective to return the tripping member 50 70 to its latched position and to store tripping energy in the tripping springs 71, the U-shaped operating member 52 being provided with shoulder portions 105 arranged to engage the extending portions 74 on the tripping member 70 to 55 move the tripping member about its pivot 51 in a counterclockwise direction. The operating handle 53 may then be moved to its uppermost position shown in Fig. 2 to reclose the circuit breaker contacts in the manner heretofore described.

- 60 It will be apparent now that the arrangement of the tripping springs 71 and the tripping member 70 is such as to provide a very compact arrangement in which the operating elements are so nested together and overlapped as to reduce to a minimum the physical dimensions of the circuit breaker.

- 65 While I have shown a particular embodiment of my invention, it will be understood, of course, that I do not wish to be limited thereto, since many modifications may be made and I, therefore, contemplate by the appended claims to cover any such modifications as fall within the true 70 spirit and scope of my invention.

What I claim as new and desire to secure by Letters Patent of the United States, is:

1. A circuit breaker comprising a pair of relatively movable contacts, an operating mechanism comprising a frame having spaced walls, each of said walls including an elongate portion provided with a guide, manually operable means supported on said frame for operating one of said contacts between open and closed circuit positions, a pivoted tripping member having a portion arranged to operate said one contact to open circuit position when said tripping member is moved to tripping position, a tripping spring disposed between said elongate wall portions, a crossbar extending between said elongate portions with its ends cooperating with said guides, a portion of said crossbar engaging said spring, an operating strap connected between said crossbar and said tripping member, whereby said tripping spring biases said tripping member to tripping position and current responsive means normally latching said tripping member out of tripping position arranged to release said tripping member for operation by said tripping spring to operate said one contact to open circuit position upon the occurrence of predetermined abnormal current conditions. 15 20 25

2. A circuit breaker comprising a pair of relatively movable contacts, an operating mechanism comprising a frame having spaced walls, each of said walls including an elongate portion provided with a guide, manually operable means supported on said frame for operating one of said contacts between open and closed circuit positions, a pivoted tripping member having a portion arranged to operate said one contact to open circuit position when said tripping member is moved to tripping position, a tripping spring disposed between said elongate wall portions, a fixed crossbar supported by said elongate portions and engaging the end of said spring adjacent said tripping member, a movable crossbar extending between said elongate portions cooperating with said guides, said movable crossbar engaging the end of said spring remote from said tripping member, an operating strap extending along said elongate wall portions and connected between said movable crossbar and said tripping member whereby said tripping spring biases said tripping member to tripping position and current responsive means normally latching said tripping member out of tripping position arranged to release said tripping member for operation by said tripping spring upon the occurrence of predetermined abnormal current conditions. 30 35 40 45 50 55

3. A circuit breaker comprising a pair of relatively movable contacts, an operating mechanism comprising a frame having spaced walls, each of said walls including an elongate portion provided with a guide, manually operable means supported on said frame for operating one of said contacts between open and closed circuit positions, a pivoted tripping member having a portion arranged to operate said one contact to open circuit position when said tripping member is moved to tripping position, a pair of spaced crossbars extending between said elongate wall portions, one of said crossbars remote from said tripping member being slidably supported in said guides, a pair of operating straps extending along said elongate wall portions, each of said straps having one end connected to said tripping member and its opposite end connected to said one crossbar, a tripping spring disposed between said elongate 60 65 70 75 80 85 90 95 98 99

walls with its respective ends engaging said spaced crossbars for biasing said tripping member to tripping position, and current responsive means normally latching said tripping member out of tripping position arranged to release said tripping member for operation by said tripping spring upon the occurrence of predetermined abnormal current conditions.

4. A circuit breaker comprising a pair of relatively movable contacts, an operating mechanism comprising a frame having spaced walls, each of said walls including an elongate portion provided with a guide, manually operable means supported on said frame for operating one of said contacts between open and closed circuit positions, a U-shaped tripping member pivoted on said frame, each leg of said U-shaped member having portions extending laterally thereof on opposite sides of the pivot point, a pair of operating straps connected respectively to said extending portions on one side of said pivot point, said portions on the other side of said pivot point being arranged to operate said one contact to open circuit position when said tripping member is operated to tripping position, a pair of spaced crossbars extending between said elongate wall portions, the one of said crossbars remote from said tripping member being slidably supported in said guides and connected to said operating straps, a tripping spring disposed between said elongate walls with its respective ends engaging said spaced crossbars for biasing said tripping member to tripping position, and current responsive means normally latching said tripping member out of tripping position arranged to release said tripping member for operation by said tripping spring to operate said one contact to open circuit position upon the occurrence of predetermined abnormal current conditions.

5. A circuit breaker comprising a pair of relatively movable contacts, an arc extinguishing chamber enclosing said contacts, an operating mechanism comprising a frame having spaced walls supported on a wall of said chamber, each of said walls including an elongate portion extending along said chamber wall and a portion overhanging an end of said chamber, said elongate portions having guides thereon, manually operable means supported on said overhanging frame portions for operating one of said contacts between open and closed circuit positions, a tripping member pivoted on said overhanging portion and arranged to operate said one contact to open circuit position when said tripping member is moved to tripping position, a tripping spring disposed between said elongate wall portions, a crossbar extending between said elongate portions cooperating with said guides, a portion of said crossbar engaging said spring, an operating strap connected between said crossbar and said tripping member whereby said tripping spring biases said tripping member to tripping position, and current responsive means normally latching said tripping member out of tripping position arranged to release said tripping member for operation by said tripping spring upon the occurrence of predetermined abnormal current conditions.

6. A circuit breaker comprising a pair of relatively movable contacts, an arc extinguishing chamber enclosing said contacts, an operating mechanism comprising a frame having spaced walls supported on a wall of said chamber, each of said walls including an elongate portion extending along said chamber wall and a portion

overhanging an end of said chamber, said elongate portions having guides therein, manually operable means supported on said overhanging frame portions for operating one of said contacts between open and closed circuit positions, a tripping member pivoted on said overhanging portion and arranged to operate said one contact to open circuit position when said tripping member is moved to tripping position, a tripping spring disposed between said elongate wall portions, a fixed crossbar supported by said elongate portions and engaging the end of said spring adjacent said tripping member, a movable crossbar extending between said elongate portions with its ends cooperating with said guides, said movable crossbar engaging the end of said spring remote from said tripping member, an operating strap extending along said elongate wall portions and connected between said movable crossbar and said tripping member whereby said tripping spring biases said tripping member to tripping position and current responsive means normally latching said tripping member out of tripping position arranged to release said tripping member for operation by said tripping spring upon the occurrence of predetermined abnormal current conditions.

7. A circuit breaker comprising a pair of relatively movable contacts, an arc extinguishing chamber enclosing said contacts, an operating mechanism comprising a frame having spaced walls supported on a wall of said chamber, each of said walls including an elongate portion extending along said chamber wall and a portion overhanging an end of said chamber, said elongate portions having guides therein, manually operable means supported on said overhanging frame portions for operating one of said contacts between open and closed circuit positions, a tripping member pivoted on said overhanging portion and arranged to operate said one contact to open circuit position when said tripping member is moved to tripping position, a pair of spaced crossbars extending between said elongate wall portions, the one of said crossbars remote from said tripping member being slidably supported in said guides, a pair of operating straps extending along said elongate wall portions, each of said straps having one end connected to said tripping member and its opposite end connected to said one crossbar, a tripping spring disposed between said elongate walls with its respective ends engaging said spaced crossbars for biasing said tripping member to tripping position, and current responsive means normally latching said tripping member out of tripping position arranged to release said tripping member for operation by said tripping spring upon the occurrence of predetermined abnormal current conditions.

8. A circuit breaker comprising a pair of relatively movable contacts, an arc extinguishing chamber enclosing said contacts, an operating mechanism comprising a frame having spaced walls supported on a wall of said chamber, each of said walls including an elongate portion extending along said chamber wall and a portion overhanging an end of said chamber, said elongate portions having guides therein, manually operable means supported on said overhanging frame portions for operating one of said contacts between open and closed circuit positions, a U-shaped tripping member pivoted on said frame, each leg of said U-shaped member having portions extending laterally thereof on opposite sides of the pivot point, a pair of operating straps connected

respectively to said extending portions on one side of said pivot point, said portions on the other side of said pivot point being arranged to operate said one contact to open circuit position when 5 said tripping member is operated to tripping position, a pair of spaced crossbars extending between said elongate wall portions, the one of said crossbars remote from said tripping member being slidably supported in said guides and connected to said operating straps, a tripping spring disposed between said elongate walls with its respective ends engaging said spaced crossbars for biasing said tripping member to tripping position, and current responsive means normally latching said tripping member out of tripping position arranged to release said tripping member for operation by said tripping spring to operate said one contact to open circuit position upon the occurrence of predetermined abnormal current conditions.

9. A circuit breaker comprising a pair of relatively movable contacts, an operating mechanism comprising a frame having spaced walls, each of said walls including an elongate portion having a slot therein, an operating member pivotally mounted on said frame remote from said slot, a switch operating arm pivotally mounted adjacent said operating member, overcenter spring means connected between said operating member and said switch operating arm for moving said arm between open and closed circuit positions with a snap action, means operatively connecting said switch operating arm with one of said contacts, a tripping member pivoted on said frame having a portion arranged to engage said switch operating arm to operate said one contact to open circuit position independently of said operating member when said tripping member is moved to tripping position, an operating strap connected to a portion of said tripping member, a pair of spaced crossbars extending between said elongate wall portions, the one of said crossbars remote from said tripping member being slidably supported in said slots and connected to said operating strap, 40 a tripping spring disposed between said elongate walls with its respective ends engaging said spaced crossbars for biasing said tripping member

to tripping position, and current responsive means normally latching said tripping member out of tripping position arranged to release said tripping member for operation by said tripping spring upon the occurrence of predetermined 5 abnormal current conditions.

10. A circuit breaker comprising a pair of relatively movable contacts, an operating mechanism comprising a frame having spaced opposed walls, each of said walls including an elongate portion 10 having a slot therein, a U-shaped operating member pivotally engaging said frame remote from said slot, a pair of spaced parallel arms having their adjacent ends pivotally engaging said frame within the legs of said U-shaped operating member, a pin carried by the other ends of said spaced arms, means operatively connecting said pin with one of said contacts, overcenter 15 spring means connected between said pin and said operating member for operating said one contact between open and closed circuit positions with a snap action, a U-shaped tripping member pivoted on said frame, each leg of said tripping member having portions extending laterally thereof on opposite sides of the pivot 20 point, a pair of operating straps connected respectively to said extending portions on one side of said pivot point, said portions on the other side of said pivot point being arranged to engage said pin for operating said one contact to open 25 circuit position against the force exerted by said overcenter spring means when said tripping member is moved to tripping position, a pair of spaced crossbars extending between said elongate wall portions, the one of said crossbars remote 30 from said tripping member being slidably supported in said slots and connected to said operating straps, a tripping spring disposed between said elongate wall portions with its respective ends engaging said spaced crossbars for biasing 35 said tripping member to tripping position, and current responsive means normally latching said tripping member out of tripping position arranged to release said tripping member for operation by said tripping spring upon the occurrence 40 of predetermined abnormal current conditions.

LEONARD J. LINDE.
